(57) **CLAIM**

The ornamental design for an air blower unit for an inflatable body, as shown and described.

DESCRIPTION

FIG. 1 is a perspective view of the air blower unit for an inflatable body according to my new design, as seen from the right front corner thereof. The dashed lines are for illustrative purposes only and do not form part of the design. FIG. 2 is perspective view as seen from the left front corner thereof.

FIG. 3 is a left side elevational view thereof.

FIG. 4 is a top plan view thereof.

FIG. 5 is a front elevational view thereof.

FIG. 6 is a right side elevational view thereof.

FIG. 7 is a rear elevational view thereof; and,

FIG. 8 is a bottom plan view thereof.

The broken line showing of the electrical cords and a power connection is included for the purpose of illustrating environmental structure and forms no part of the claimed design.
